UNITED STATES PATENT OFFICE.

JAMES FALLOWS, OF PHILADELPHIA, PENNSYLVANIA.

TOY.

SPECIFICATION forming part of Letters Patent No. 352,401, dated November 9, 1886.

Application filed February 15, 1886. Serial No. 191,975. (No model.)

To all whom it may concern:

Be it known that I, JAMES FALLOWS, a citizen of the United States, residing at Philadelphia, in the county of Philadelphia and State 5 of Pennsylvania, have invented certain new and useful Improvements in Toys; and I do hereby declare the following to be a full, clear, and exact description of the invention, such as will enable others skilled in the art to which 10 it appertains to make and use the same.

My invention relates to the manufacture of that class of toys and similar articles that have secured thereto or mounted thereon tin figures of men, animals, &c.

15 The objects of my improvement are to lessen the cost of construction, to add strength and firmness to the article, and at the same time produce a toy that will be comparatively noiseless when rolled along the floor, and one that 20 will not scratch or bruise the furniture of the room when brought in contact therewith. To accomplish these objects I make the pedestal or platform of the toy of wood, and attach the tin figures and any desired mechanism in the 25 manner hereinafter described.

Heretofore toys of this class have always been constructed with a tin platform, in order that the surmounting figure may be easily and cheaply secured thereto by soldering. As a 30 consequence the toy is frail and easily broken, and when rolled along the floor produces a loud, disagreeable, rattling noise. Besides, when striking the furniture of the room, no matter how slight the blow, an unsightly 35 scratch or bruise is sure to follow. All of these objections are overcome by making the platform of wood and joining the parts together in the manner herein shown.

In the accompanying drawings, Figure 1 is 40 a side elevation of a toy having my improvements therein. Fig. 2 is an enlarged section showing the manner of attaching the axles and the tin disks or plates to which the figures are soldered. Fig. 3 is a sectional side elevation. Fig. 4 are details of the axle bearings and supports. Fig. 5 are detailed views of the plates or disks to which the figures are soldered. Fig. 6 is a view of the axle-bearings and their connecting-piece removed from the 50 wooden platform.

A is the wooden platform of the toy; B, the

figure mounted thereon; C, the wheels upon which the toy rolls along the floor.

c is the axle for the wheels.

D D are the supports for the axles. These 55 supports are made of sheet-tin corrugated to increase the strength and bent in the shape shown in Fig. 4.

d d are spurs or projections formed on both sides of the supports D. These spurs enter or 60 are forced into the sides of the wooden platform A, (see Fig. 2,) thus preventing the supports from moving back or forward.

d' d' are narrow strips of tin extending across the under side of the platform. These strips 65 are soldered at the ends to the supports D D, in the position shown in Fig. 6, thus securely connecting them together and fixing them in the proper position. To more securely fasten the supports D D in position and provide for any 70 shrinkage of the wooden platform, the strips *d' d'* may be made to extend only partially across, in which case they would be tacked to the under side of the platform close to the supports D.

E E are two small disks or plates of tin secured to the wooden platform by means of a tack passing through both platform and disk. To these plates or disks the surmounting figure is soldered, as shown in Fig. 1. 75

In small toys, instead of the tin plates or disks E E, a tack or rivet having a large head may be used. These plates may also be made of brass or any metal to which solder will readily adhere, tin-plate being used simply on 85 account of its cheapness.

Having thus described my invention, what I claim as new, and desire to secure by Letters Patent of the United States, is—

1. In a toy, the combination, with the wooden 90 platform A and suitable supporting means therefor, substantially as described, of the metallic figure B, and the metallic plate or plates E, provided with tacks for insertion into or through the wooden platform, and having the 95 metallic figure soldered to the upper surface of said plate or plates, substantially as and for the purposes herein set forth.

2. The combination of the wooden pedestal or platform A, the soldering plate or plates E, 100 secured to the platform, a surmounting metal figure, B, the axle-supports D, having the spur

or spurs *d* and attaching-strip *d'*, and the wheels *C*, all arranged substantially as and for the purpose described.

3. The wooden platform or pedestal *A*, having a surmounting figure, in combination with the wheels *C*, and supports *D*, having their tops bent to clasp around the edge of the platform, and being provided with the attaching-strips *d'*, said attaching-strips extending

only partially across the under side of the wooden platform, substantially as described.

In testimony whereof I affix my signature in presence of two witnesses.

JAMES FALLOWS.
